R. C. NEWHOUSE

CRUSHER

Filed Jan. 19, 1925

UNITED STATES PATENT OFFICE.

RAY C. NEWHOUSE, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

CRUSHER.

Application filed January 19, 1925. Serial No. 3,230.

This invention relates in general to improvements in the art of disintegrating relatively hard substances, and relates more specifically to improvements in the construction and operation of crushers for reducing substances such as rock, coal, ore and the like.

An object of the invention is to provide an improved crusher which is simple in construction and efficient in operation.

Some of the more specific objects of the invention are as follows:

To provide improved driving mechanism for crushers including interconnected gyratory and actuating means for a crushing member located at opposite ends thereof, and means whereby such mechanism may be effectively protected against damage due to entry of grit and dirt.

To provide an improved simple, compact and highly efficient gyratory crusher structure wherein a high speed motor may be employed to gyrate the movable crushing member at relatively low speed.

To provide other improvements in crusher construction whereby the cost of construction of such machines is reduced to a minimum and the efficiency is increased to a maximum.

Some of the novel features of crusher construction disclosed but not specifically claimed herein form the subject of the co-pending application Serial Number 588,401 filed September 15, 1922.

A clear conception of an embodiment of the invention and of the operation of machines constructed in accordance therewith, may be had by referring to the drawing accompanying and forming a part of this specification in which like characters designate the same or similar parts in the several views.

Fig. 1 is a central vertical section through an improved motor driven gyratory crusher.

Fig. 2 is a transverse horizontal section through the improved crusher, the section being taken directly above the speed reduction gearing and the view being taken in a downward direction.

The improved crusher which has been illustrated as being of the well known gyratory type, comprises in general a stationary annular crushing member or concave 3 mounted within an upper frame 4, and a relatively gyratable crushing member or head 2 located within and cooperating with

the concave 3 to form an annular downward converging crusher chamber 13. The gyratory head 2 is of frusto-conical shape and is rigidly secured to an upright hollow suspension shaft 5 which is supported by a spherical suspension bearing 18 and a guide bearing 19 formed in a relatively heavy spider 10 which is rigidly attached to the upper frame 4. The crushing chamber 13 has an upper inlet 12 accessible through the space between the arms of the spider 10, and a lower annular outlet 14 communicating with the interior of a lower frame 11 upon which the upper frame 4 is mounted. The interior of the lower frame 11 communicates with a final discharge spout 35. The upper and lower frames 4, 11 are mounted upon a suitable foundation 16 and the lower frame 11 is provided with an integral bearing hub 23 having a renewable bushing 75 or sleeve 22 therein.

The lower extremity of the hollow suspension shaft 5 extends into the bushing 22 and is fitted within a bore of a rotary eccentric 6 the outer surface of which engages the bore of the bushing 22. The eccentric 6 is located closely adjacent to the lower end of the crushing head 2 and an upper cap 26 engages the shaft 5 and the bushing 22 in order to prevent dirt from entering the region of the eccentric 6. The eccentric 6 is mounted upon a thrust bearing 21 secured to the lower extremity of the frame 11 and carries three depending stub-shafts 30 upon each of which is mounted a spur gear 29. The spur gears 29 mesh with an internally toothed stationary member 17 which is secured to the frame 11, and also mesh with a central pinion 28 which is rigidly secured to the slotted lower extremity 20 of the upright drive shaft 7. The lower portion of the drive shaft 7 is supported in a guide bearing 27 formed within the eccentric 6 and the shaft 7 extends upwardly through the hollow suspension shaft 5.

The upper portion of the shaft 7 is supported in a combined thrust and guide bearing 15 located above the suspension bearing 18 of the shaft 5. The upper extremity of the drive shaft 7 is direct connected to a prime mover or electric motor 9 by means of a flexible coupling 8, the motor 9 being supported from the spider 10 by virtue of intermediate stationary supporting element 32. The suspension and thrust bearing 15, the 110

2

suspension bearing 18, and the guide bearing 19 are accessible for lubrication through openings in the supporting element 32. The bearings of the eccentric 6, the bearing 27 and the gearing connecting the shaft 7 with the eccentric 6 may be effectively lubricated by means of oil admitted through an inlet 24 and discharging through an outlet 25. The gearing connecting the shaft 7 and the eccentric 6 is inclosed by means of a removable lower cap 31 thus making this gearing readily accessible and removable.

During normal operation of the crusher the motor 9 is operating at relatively high speed and is transmitting rotary motion through the coupling 8 and shaft 7 to the central pinion 28. The high speed rotary motion of the pinion 28 is transmitted to the idler pinions 29 which are caused to roll upon the internal teeth of the element 17 and thereby produce relatively slower rotation of the eccentric 6. By providing a proper number of teeth on the pinion 28, gears 29 and the element 17 comprising the planetary gear set, any desired speed of rotation of the eccentric 6 may be attained. The rotating eccentric 6 produces gyration of the suspension shaft 5 and of the head 2 about the center of generation on the spherical suspension bearing 18, and relatively to the stationary concave 3. This relative gyratory motion of the members 2, 3 produces gradual disintegration or reduction of material admitted to the crushing chamber 13 through the inlet 12, the reduced material being gradually advanced through the chamber 13 and eventually discharged by gravity through the annular outlet 14 and through the spout 35 associated with the lower frame 11.

From the foregoing description it will be obvious that a high speed electric motor 9 may readily be utilized to effectively operate or gyrate the crusher head 2 at relatively low speed. The planetary drive connecting the motor 9 and the operating eccentric 6 is of simple and efficient construction and is readily accessible for inspection and removal. The various elements of the structure may be readily lubricated and may be thoroughly protected against entry of dirt and grit. By locating the motor 9 above the crusher, this motor is also protected against possible damage.

It should be understood that it is not desired to limit the invention to the exact details of construction and operation herein shown and described, for various modifications within the scope of the claims may occur to persons skilled in the art.

It is claimed and desired to secure by Letters Patent:—

1. In combination, relatively gyratable crushing members having a concentric end guide bearing, means disposed at one end of

said members remote from said bearing for relatively gyrating the same, means disposed at the opposite end of said members for actuating said gyrating means, and speed reducing means disposed at said first mentioned end of said members and connecting said actuating and said gyrating means. 70

2. In combination, relatively gyratable crushing members having a concentric upper guide bearing, means located below said members for relatively gyrating the same, means located above said members for actuating said gyrating means, and speed reduction gearing located below said members and connecting said actuating and said gyrating 80 means.

3. In combination, relatively gyratable inner and outer crushing members having a concentric upper guide bearing, means located directly below said members for relatively gyrating the same, means operable at high speed and located above said members for actuating said gyrating means, and speed reduction gearing located below said members and connecting said actuating and said 90 gyrating means. 85

4. In combination, relatively gyratable inner and outer crushing members having a concentric upper guide bearing, an eccentric located directly below said members for relatively gyrating the same, a high speed motor located above said members for actuating said eccentric, and planetary gearing located below said members and connecting said motor and said eccentric. 100

5. In combination, relatively gyratable inner and outer crushing members, a guide bearing for said inner member disposed concentric with and above said outer member, an eccentric located below said members for gyrating said inner relatively to said outer member, a motor located above said members, a shaft associated with said motor and extending downwardly through said members, and planetary gearing connecting said 110 shaft and said eccentric. 105

6. In combination, relatively gyratable inner and outer crushing members, a guide bearing for said inner member disposed concentric with and above said outer member, an eccentric located directly below said members for gyrating said inner member relatively to said outer member at relatively low speed, a high speed motor located above said members, a shaft associated with said motor 115 and extending downwardly through said members, and planetary gearing located below said eccentric and connecting said shaft with said eccentric. 120

7. In combination, a concave, a crusher head located within said concave, a guide bearing for said head disposed concentric with and at one end of said concave, and an eccentric located at the opposite end of said concave for gyrating said head relatively to 130

said concave, a motor located at the guide bearing end of said head, a shaft associated with said motor and extending longitudinally of said head, and speed reducing gear-

second member relatively to said axis, a motor having a rotor co-axial with said axis, and speed reducing gearing drivingly connecting said rotor and said element. 35

5 ing connecting said shaft and said eccentric.

11. In combination, an annular crushing member, a second crushing member located within said annular member, an eccentric for positively gyrating said second member,

10 an eccentric located below said members for relatively gyrating the same, a motor located above said members and said bearing, a shaft associated with said motor and extending through said members, and planetary gear-

40 eccentric being located below said second member, a high speed motor located above said second member, and a mechanical connection between said motor and said eccentric, said connection comprising a driving shaft penetrating said head and speed 45 reducing gearing associated with said shaft.

15 8. In combination, relatively gyratable inner and outer crushing members, a guide bearing for said inner member disposed concentric with and above said outer member, an eccentric located below said members for relatively gyrating the same, a motor located above said members and said bearing, a shaft associated with said motor and extending through said members, and planetary gear-

50 ing connecting said shaft and said eccentric below the latter.

9. In combination, an annular crushing member, a second crushing member located within said annular member, a guide bearing 20 for said second member disposed co-axial with said annular member, an eccentric for relatively gyrating said members, a motor disposed co-axial with said annular member, and speed reducing gearing drivingly connecting said motor and said eccentric.

12. In combination, relatively gyratable crushing members having adjacent feed and discharge ends, a rotary element for relatively gyrating said members, said element 55 being located at one of said ends of said members, high speed driving means located at the other of said ends of said members, and a rotary motion transmitting connection between said driving means and said element, said connection comprising a driving shaft penetrating said members and speed reducing gearing associated with said shaft.

In testimony whereof, the signature of the inventor is affixed hereto.

RAY C. NEWHOUSE.
